UNITED STATES PATENT OFFICE

NELS BERGGREN, OF CHICAGO, ILLINOIS, ASSIGNOR TO FEDERAL ELECTRIC COMPANY, OF CHICAGO, ILLINOIS

DESIGN FOR A SIGN BORDER

Application filed March 21, 1929. Serial No. 30,576. Term of patent 3½ years.

To all whom it may concern:

Be it known that I, NELS BERGGREN, a citizen of the United States, residing at Chicago, in the county of Cook and State of Illinois, have invented a new, original, and ornamental Design for Sign Borders, of which the following is a specification, reference being had to the accompanying drawing, forming a part thereof.

Referring to the drawing:

The figure is a view illustrating a portion of a sign border design embodying my invention as applied in curved borders.

I claim:

The ornamental design for a sign border as shown.

NELS BERGGREN.
